UNITED STATES PATENT OFFICE.

GEORGE WAGNER, OF JEFFERSON CITY, MISSOURI.

DESIGN FOR A CROSS.

SPECIFICATION forming part of Design No. 15,482, dated October 21, 1884.

Application filed July 5, 1884. Term of patent 3½ years.

To all whom it may concern:

Be it known that I, GEORGE WAGNER, a citizen of the United States, and a resident of Jefferson City, in the county of Cole and State of Missouri, have invented a certain new and original Design for Crosses; and I do hereby declare that the following is a full, clear, and exact description of the invention, which will enable others skilled in the art to which it applies to make and use the same, reference being had to the accompanying drawings, which form a part of this specification, and in which—

Figure 1 is a front view of the cross. Fig. 2 is a side view of the same, and Fig. 3 is a top view.

Similar letters of reference indicate corresponding parts in all the figures.

This design relates to crosses; and it consists in the novel and ornamental design for a cross which will show cross-shaped configurations when seen from any point, as will be more fully described and claimed.

In the drawings, the letter A indicates a rearwardly and upwardly narrowing base having feet B, and C indicates the upright stem of the

cross, and D the cross-piece of the same. This base, feet, stem, and cross-piece consist of longer slats E, having serrated ends, and smaller cross-pieces F, which slats and cross-pieces have notches G and H between their points of connection with each other, so that the entire cross shows a light open design showing cross-shaped configurations at all points. 35

I claim—

The design for a cross, consisting of an upwardly and rearwardly narrowing base surrounded by a cross and mounted upon feet, the said base, feet, and cross consisting of longer slats and shorter cross-pieces, the said slats and cross-pieces being notched between their points of connection and having serrated ends, as shown and described. 40

In testimony that I claim the foregoing as my own I have hereunto affixed my signature in presence of two witnesses.

GEORGE WAGNER.
